Application February 15, 1949, Serial No. 76,464

Claims priority, application Netherlands April 6, 1948

8 Claims. (Cl. 315—24)

1

The invention relates to a device for producing sawtooth voltages and to radar apparatus comprising such a device for producing deflection voltages required for a polar position indicator.

For producing sawtooth voltages devices are known which supply the time integral of a pulse-shaped voltage. One known device of this kind (see for example "Wireless World" June 1946, pages 176, 177, "Linear sawtooth oscillator") is that which comprises a grid-controlled electron tube, the anode voltage source of which has connected to it the series combination of an anode resistance of the tube, a condenser and a second resistance, the control-grid of the tube being connected via the second resistance and an auxiliary voltage source to the cathode of the tube, the said condenser being connected as a negative feedback condenser between the anode and the control-grid of the tube and the pulse-shaped voltage to be integrated being supplied by the auxiliary voltage source which is caused to operate in the rhythm of the sawtooth oscillation to be produced.

According to the invention, the practical ranges of possible employment of the above described devices are materially extended by choosing the supply voltages of the tube to be such that when the auxiliary voltage source is inoperative, an appreciable anode rest current occurs, so that when a constant auxiliary voltage of negative polarity becomes effective the anode potential increases substantially linearly with time.

In the devices assumed in the foregoing as being known, the anode rest current of the electron tube, which as a rule, operates as a switch, is zero or very low, and it can only be ensured that the anode potential decreases linearly with time.

By adjusting the tube, in accordance with a further feature of the invention, as a class-A amplifier it is ensured that, when a constant auxiliary voltage becomes effective the anode potential varies substantially linearly with time in a sense varying with the polarity of the auxiliary voltage. By a class A amplifier is meant one in which the grid bias voltage permits a steady anode current flow of such value that the anode current varies directly as the grid voltage for the complete cycle of 360 degrees. The resulting output voltage for an ideal class A amplifier is an exact reproduction of the grid voltage.

The latter adjustment, the class-A amplifier adjustment, is particularly suitable for use in

2

radar apparatus in which, for scanning the image screen of the polar position indicator in the direction of a rotating radius vector use is made of sawtooth deflection voltages which are modulated by quadrature sinusoidal alternating voltages. The deflection voltages required for this purpose are produced with the use of two devices according to the invention by employing therein two quadrature sinusoidal alternating voltages as auxiliary voltages.

In order that the invention may be more clearly understood and readily carried into effect, it will now be described more fully with reference to the accompanying drawing.

Fig. 1 shows one embodiment of the device according to the invention in its simplest form and

Figs. 2, 3 and 4 show associated diagrams illustrating the adjustment and the operation.

Fig. 5 shows a device according to the invention which has been found to be useful in practice and

Figs. 6 and 7 show diagrams illustrating Fig. 5.

Fig. 8 is a block diagram of a polar position indicator for a radar system.

In the device shown in Fig. 1 a pentode electron tube 1 is connected to an anode voltage source 2. The anode lead of the tube comprises an anode resistance 3, which is connected in series with a negative feedback condenser 4 connected between anode and control-grid of the tube, a grid resistance 5 and an auxiliary voltage source 6. The series combination of the grid resistance 5 and the auxiliary voltage source 6 is shunted by a short-circuiting switch 7 which is

closed in rest position of the device. The control-grid circuit of the electron tube comprises in addition a grid bias voltage source 8 which serves to adjust the working point of the tube 1 in rest position.

Fig. 2 shows the variation of the anode current (I_a) of the tube with the control-grid voltage (V_g). According to the invention, the value of the control-grid bias voltage supplied by battery 8 is chosen to be such that with the short-

circuiting switch 7 closed in rest position an appreciable anode rest current occurs in the tube 1; for example the anode rest current may correspond to the working point designated 9 in Fig. 2, if only sawtooth voltages varying in a positive

sense are required to be produced, or else the working point may correspond to point 10 of Fig. 2 so long as the polarity of the sawtooth voltage to be produced alternates.

Starting with the rest position and the associated adjusted working point 10, the operation

of the circuit shown in Fig. 1 may be described as follows. If the auxiliary voltage is negative-going and is independent of time, the potential of the control-grid, on the short-circuiting switch 7 being opened, will be decreased owing to the auxiliary voltage source becoming operative. This decrease in control-grid potential entails a decrease in anode current of the tube 1 and hence an increase in anode potential. This increase in anode potential is transmitted by the negative feedback condenser 4 to the control-grid of the tube 1 and counteracts the initial variation of the control-grid potential in such manner that the latter varies to a very small extent and the anode potential varies directly as time. The rate of variation of the anode- and control-grid potential is determined by the time constant of the circuit of the condenser 4, which is chiefly determined by the value of the condenser 4 and that of the resistance 5 so long as the amplification factor of tube 1 is sufficiently high. Particularly if the auxiliary voltage considerably exceeds the variation of the grid potential, the following relation obtains for the variation of the anode potential:

$$\frac{dV_a}{dt} = \frac{V_r}{RC}$$

in which V_a designates the potential difference between anode and cathode of the tube 1, V_r the value of the auxiliary voltage and R and C the values of resistance 5 and condenser 4 respectively.

As may be seen from the above relation, the variation of the anode potential is directly proportional to the value of the auxiliary voltage, and is of opposite polarity. The latter fact is made use of, in accordance with the invention, to produce a sawtooth voltage varying in a positive or a negative sense by choice of the polarity of the auxiliary voltage which is periodically caused to be effective.

Referring to Fig. 1, the sawtooth voltage occurs across output terminals 12, which are connected to an output resistance 11 and of which one is earthed, the other being connected to the anode of tube 1 by way of a coupling condenser 13.

If, as is shown in the time diagram of Fig. 3a, the short-circuiting switch 7 is opened for a period t_1-t_2 the anode potential V_a varies, according to the time diagram of Fig. 3b, linearly with time during the said period, the anode potential being increased if the auxiliary voltage is negative. On the switch 7 being closed at the instant t_2 , the anode potential is rapidly decreased to the initial value. The maximum amplitude of the sawtooth voltage occurring is proportional to the value of the auxiliary voltage applied. Referring to Fig. 3b, a full line a denotes the variation of the sawtooth voltage with approximately maximum permissible amplitude, which is reached, for example, when the auxiliary voltage is -200 volts, whereas a dotted line b shows the sawtooth voltage when use is made of an auxiliary voltage of -80 volts. In both cases the anode voltage source may supply a voltage of, say, 250 volts. In rest position the working point corresponds to point 9 of Fig. 2.

Fig. 4 shows time diagrams in which in rest position the working point of tube 1 corresponds to point 10 of Fig. 2. If, as shown in Fig. 4a, the short-circuiting switch 7 is opened for a period t_1-t_2 , the anode potential of the tube varies in accordance with the full line c of the

diagram 4b if use is made of an auxiliary voltage of, for example, -100 volts, and in accordance with dotted line d if use is made of an auxiliary voltage +100 volts.

Fig. 5 shows a circuit-arrangement of a device according to the invention for producing alternating sawtooth voltages modulated by a sinusoidal alternating voltage, said arrangement having been found to be preferred in practice. The anode voltage source 2 has again connected to it the series combination of an anode resistance 3, a negative feedback condenser 4, a grid resistance 5 and an auxiliary voltage source, the latter supplying an alternating sinusoidal voltage and being designated 6'. The grid bias battery 8 of Fig. 1 is replaced by a cathode resistance 8' included in the cathode lead of tube 1 and shunted by a smoothing condenser 8''. The output voltage is taken from the anode of tube 1 through a coupling condenser 13 and fed to an output resistance 11 having output terminals 12.

The grid resistance 5 and the auxiliary voltage source 6' are connected in parallel with two diodes 14, 15 having series resistances 16, 17 and acting as the short-circuiting switch 7 of Fig. 1. The diodes 14, 15 are connected in parallel and in opposite senses and, in rest position of the device, stabilise the working point of the tube in accordance with the grid bias supplied by the cathode resistance 8', in such manner that tube 1 is adjusted as a class-A amplifier. The two diodes 14, 15 are periodically cut off simultaneously by pulse-shaped voltages of opposite polarity fed to them across connecting terminals 18, 19 as shown in the figure. The anode potential of the tube 1 thus varies periodically in sawtooth form in a manner similar to that explained with reference to the preceding figures, the maximum amplitude of the sawtooth oscillations produced varying, however, since the auxiliary voltage varies sinusoidally with time, in accordance with the variation of the auxiliary sine voltage in the manner shown in Fig. 6. As may be seen therefrom and will be obvious from comparison with Fig. 4, the sawtooth voltage is invariably increased linearly with time during one half wave of the auxiliary sine voltage and is invariably decreased linearly with time during the next following half wave of the auxiliary sine voltage.

By using two devices as shown in Fig. 5 with the use of quadrature sine voltages as auxiliary voltages for the two devices, sawtooth voltages are produced which are modulated by the said auxiliary voltages and which are consequently particularly suitable for use as deflection voltages for scanning the image screen of a polar position indicator in a radar apparatus in the direction of a rotating radius vector. Such an arrangement is illustrated in Fig. 8.

If the output sawtooth voltage is taken from the anode of tube 1 through a coupling condenser, the position of the zero axis of the alternating output voltage relatively to the starting points of the linearly varying flanks of the sawtooth voltage must, however, be allowed for. For use in radar apparatus it is frequently desirable for the said starting points to be located on the said zero axis. The direct current component which with a view to obtaining the object is to be added to the output voltage and which varies with the value of the auxiliary voltage can be produced, in the device according to the invention, in a particularly simple manner by con-

necting, in series with the negative feedback condenser, between the anode and the control-grid of tube 1 an auxiliary resistance 20, the value of which is suitably chosen relatively to the grid resistance 5. This resistance has the effect that during the flanks of the generated sawtooth voltage varying linearly with time the output voltage has added to it a supplementary voltage of constant value, which constitutes such a fraction of the auxiliary voltage 6' as is determined by the ratio between resistance 20 and the grid resistance 5. By adjusting the value of the resistance 20 at any constant value of the auxiliary voltage 6' in such manner that the desired position of the zero axis of the output voltage is obtained, this favourable position of the zero axis of the output voltage will also occur automatically at other values of the auxiliary voltage, as is shown in Fig. 7 by a full line and a dotted line (e and f respectively) for output voltages of widely different values at a constant value of the resistance 20.

What I claim is:

1. Apparatus for generating a sawtooth voltage having a predetermined frequency comprising an electron discharge tube having a cathode, a control grid and an anode, an anode resistance, a grid resistance, means to apply a constant positive voltage relative to said cathode to said anode through said anode resistance, means to apply a constant negative voltage relative to said cathode to said grid through said grid resistance, a negative feedback capacitance connected between said anode and said grid, a source of auxiliary voltage interposed between said grid resistance and said cathode, and means periodically to render said auxiliary source alternately operative and inoperative with respect to said grid at a rate corresponding to said predetermined frequency, said constant positive and negative voltages having respective magnitudes at which an appreciable anode current flows through said tube in the intervals in which said source is inoperative whereby an anode current varying linearly with time is produced in the intervals in which the source is operative.

2. Apparatus for generating a sawtooth voltage having a predetermined frequency comprising an electron discharge tube having a cathode, a control grid and an anode, an anode resistance, a grid resistance, means to apply a constant positive voltage relative to said cathode to said anode through said anode resistance, means to apply a constant negative voltage relative to said cathode to said grid through said grid resistance, a negative feedback capacitance connected between said anode and said grid, a source of auxiliary voltage interposed serially between said grid resistance and said cathode, and switching means bridging said serially connected source and grid resistance periodically to render said auxiliary source alternately operative and inoperative with respect to said grid at a rate corresponding to said predetermined frequency, said constant positive and negative voltages having respective magnitudes at which an appreciable anode current flows through said tube in the intervals in which said source is inoperative whereby an anode current varying linearly with time is produced in the intervals in which the source is operative, said auxiliary voltage being constituted by an alternating potential whose frequency is small with respect to said predetermined frequency.

3. Apparatus for generating a sawtooth voltage having a predetermined frequency comprising an electron discharge tube having a cathode, a control grid and an anode, an anode resistance, a grid resistance, means to apply a constant positive voltage relative to said cathode to said anode through said anode resistance, means to apply a constant negative voltage relative to said cathode to said grid through said grid resistance, a negative feedback capacitance connected between said anode and said grid, a source of auxiliary voltage interposed between said grid resistance and said cathode, means periodically to render said auxiliary source alternately operative and inoperative with respect to said grid at a rate corresponding to said predetermined frequency, said constant positive and negative voltages having respective magnitudes at which said tube acts as a class A amplifier, whereby an anode current varying linearly with time is produced in the intervals in which the source is operative, and an output circuit coupled to said anode to derive the sawtooth voltage therefrom.

4. Apparatus for generating a sawtooth voltage having a predetermined frequency comprising an electron discharge tube having a cathode, a control grid and an anode, an anode resistance, a grid resistance, a constant voltage supply having a positive terminal connected through said anode resistance to said anode and a negative terminal connected to said cathode, a resistor-condenser parallel network connected at one end to said cathode and at the other end through said grid resistance to said grid to provide a bias voltage therefor, said constant voltage and said bias voltage having respective magnitudes at which said tube operates as a class A amplifier, a negative feedback capacitance connected between said anode and said grid, an auxiliary voltage source interposed between said grid resistance and said network, and means periodically to render said auxiliary source alternately operative and inoperative with respect to said grid at a rate corresponding to said predetermined frequency.

5. Apparatus for generating a sawtooth voltage having a predetermined frequency comprising an electron discharge tube having a cathode, a control grid and an anode, an anode resistance, a grid resistance, a constant voltage supply having a positive terminal connected through said anode resistance to said anode and a negative terminal connected to said cathode, a resistor-condenser parallel network connected at one end to said cathode and at the other end through said grid resistance to said grid to provide a bias voltage therefor, said constant anode voltage and said bias voltage having respective magnitudes at which said tube operates as a class A amplifier, a negative feedback capacitance connected between said anode and said grid, an auxiliary voltage source interposed between said grid resistance and said network, and means periodically to render said auxiliary source alternately operative and inoperative with respect to said grid at a rate corresponding to said predetermined frequency, said last named means including a diode connected across the series circuit formed by said auxiliary source and said grid resistance, and means to apply rectangular pulses to said diode to render it periodically conductive.

6. Apparatus for generating a sawtooth voltage having a predetermined frequency comprising an electron discharge tube having a cathode, a control grid and an anode, an anode resist-

ance, a grid resistance, a constant voltage supply having a positive terminal connected through said anode resistance to said anode and a negative terminal connected to said cathode, a resistor-condenser parallel network connected at one end to said cathode and at the other end through said grid resistance to said grid to provide a bias voltage, said constant voltage and said bias voltage having respective magnitudes at which said tube operates as a class A amplifier, a negative feedback capacitance connected between said anode and said grid, an auxiliary alternating voltage source interposed between said grid resistance and said network and having a frequency which is small with respect to 15 said predetermined frequency, and means periodically to render said auxiliary source alternately operative and inoperative with respect to said grid at a rate corresponding to said predetermined frequency and including a pair of diodes connected in parallel opposition across the series circuit formed by the series connected grid resistance and auxiliary source and means to apply periodic rectangular pulses in phase opposition to said diodes to render said diodes simultaneously conductive periodically at a rate corresponding to said predetermined frequency.

7. Apparatus for generating a sawtooth voltage having a predetermined frequency comprising an electron discharge tube having a cathode, a control grid and an anode, an anode resistance, a grid resistance, a constant voltage supply having a negative terminal connected to said cathode and a positive terminal connected through said anode resistance to said anode, means to apply a constant negative voltage relative to said cathode to said grid through said grid resistance, said constant voltages having respective magnitudes at which said tube operates as a class A amplifier, a negative feedback capacitance connected between said anode and said grid, an auxiliary voltage source interposed between said grid resistance and said cathode, means periodically to render said source alternately operative and inoperative with respect to 45 said grid at a rate corresponding to said predetermined frequency, an output circuit for deriving the sawtooth voltage from said anode and including a coupling capacitor connected to said

anode, and means for varying the direct-current component of the sawtooth voltage including a variable resistance interposed between said grid and said negative feedback capacitance.

5 8. In a plan position indicating radar system provided with a cathode-ray tube having first and second deflection means, apparatus for generating first and second deflection voltages to be applied to said deflection means, said apparatus being constituted by two sawtooth generators operating at a predetermined frequency each having an electron discharge tube including a cathode, a control grid and an anode, an anode resistance, a grid resistance, a constant voltage supply having a positive terminal connected through said anode resistance to said anode and a negative terminal connected to said cathode, a resistor-condenser parallel network connected at one end to said cathode and at the other end through said grid resistance to said grid to provide a bias voltage therefor, said constant voltage and said bias voltage having respective magnitudes at which said tube operates as a class A amplifier, a negative feedback capacitance connected between said anode and said grid, an auxiliary voltage source interposed between said grid resistance and said network and means periodically to render said auxiliary source alternately operative and inoperative with respect to said grid at a rate corresponding to said predetermined frequency, the auxiliary voltages of the two generators being constituted by two alternating sine voltages in phase quadrature whose frequency corresponds to the scanning rate of the plan position indicating system.
